Des. 232,617
Patented Sept. 3, 1974

232,617

HEAD FOR MAGNETIC BROOM OR THE LIKE

Albert W. Albrecht, Jr., 380 Mary Lane,
Crystal Lake, Ill. 60014

Filed June 9, 1972, Ser. No. 261,569

Term of patent 14 years

Int. Cl. D4—01

U.S. Cl. D7—180

Fig. 1

Fig. 2

Fig. 3

FIG. 1 is a top front perspective view of a head for magnetic broom or the like showing my new design, shown in use with a broom handle, which broom handle is shown in broken lines for illustrative purposes only and forms no part of the claimed design;

FIG. 2 is a top front perspective view from the left quarter;

FIG. 3 is a bottom rear perspective view, and

FIG. 4 is a side view showing my new design

I claim:

The ornamental design for a head for magnetic broom or the like, substantially as shown and described.
